UNITED STATES PATENT OFFICE

ALFRED H. SMITH, OF AUBURN, RHODE ISLAND, ASSIGNOR TO FULFORD MFG. CO., A CORPORATION OF RHODE ISLAND

COVER AND INITIAL MOUNTING

Application filed April 12, 1932. Serial No. 604,727.

This invention relates to the mounting of an ornamental member in position on some article of personal apparel, bag or the like, and has for one of its objects to provide an attachable mount for a character or cover member which may be positioned upon some desired article at the time the same is sold at retail to the customer.

Another object of the invention is the provision of a construction by which the character, such as an initial or the like, may be detachably mounted in position and removed for changing the same if desired.

Another object of the invention is the provision of a detachable cover for one of the members or parts of a snap fastener, more particularly the socket member, the construction being such that the cover may be detached and removed from position or attached thereto at will.

A further object of the invention is the provision of means for preventing the character plate or cover from relative rotation with respect to the part upon which it is mounted so that the same relation of the parts may be always retained.

With these and other objects in view, the invention consists of certain novel features of construction, as will be more fully described, and particularly pointed out in the appended claims.

In the accompanying drawing:

Fig. 1 is a top plan view of the initial mounted upon a piece of flexible material such as cloth, leather or the like.

Fig. 2 is a bottom plan view of the structure of Fig. 1 with the material such as cloth, leather or the like on which it is mounted partially broken away to expose the recessed edge.

Fig. 3 is a perspective view of the body member of the fastener or mounting member with the character plate or cover removed.

Fig. 4 is a perspective view looking at the bottom of the character member or cover.

Fig. 5 is a section on line 5—5 of Fig. 1.

I have chosen to illustrate this invention more particularly with reference to the socket member of a snap fastener, which is usually formed in two parts, a body and a socket. At 50 times there has been used a third part or cover for the body which has been made of celluloid or the like rolled about the body before it is secured to a piece of fabric or leather so that when the flanged socket is forced into the 55 body to clamp the same to the fabric or leather, the celluloid cover is by this means held in position. By this invention a detachable cover may be positioned over the body of the socket fastener after the same is in position, 60 and by reason of the cover having a resilient edge it may be detached therefrom to be changed if it becomes worn or defaced in any way. Further, this cover may be provided with a character or initial for identification 65 which may be snapped into position by the retail merchant at the time the same is sold to the customer so that the article may be marked with the initial of the purchaser for identification purposes or with an emblem of 70 an organization to which the purchaser may belong, and of course in this latter use of the invention, it is immaterial whether the body member is held by means of the socket portion of a snap fastener or with any other 75 means for securing the body in its desired position, as a bag or the like; and the following is a detailed description of the present embodiment of this invention illustrating the preferred means by which these advantageous 80 results may be accomplished.

With reference to the drawing, 10 designates a piece of material which may be fabricated cloth, leather or other sheet material to which the device is attached and 11 designates 85 the head portion or body member which is generally circular in form with a rolled rim 12 and an annular depression 13 leaving a raised portion 14 in the center thereof. The under side of this body is rolled inward to 90

provide an edge 15 for engagement with the material 10 and this body is secured to the material by a socket part 16 having a flange 17 to engage the other side of the material 10 to which it is attached and with an inwardly extending collar 18 which extends through an opening in the material 10 and engages the inclined surface 19 formed by the deflection of the stock at 13 to cause this collar to be forced outwardly as illustrated in Fig. 5 to rivet the parts in assembled relation with the flange 17 binding the fabric or material 10 between it and the inwardly curved extending edge 15 of the body part 11.

15 The construction which I have illustrated provides a socket part for the reception of a stud member of a snap fastener that these parts may be secured together, although in certain uses of the invention it is immaterial 20 what sort of a part 16 is provided for holding the body in position on the fabric.

A cover member 20 is in the form of a shell which is dome shaped as at 21 and provided with an inwardly rolled edge 22 which is slit 25 as at 23 to provide fingers and afford easier operation of the tools in rolling the same inwardly and also provide a resiliency in this rolled edge permitting the cap member 20 to be snapped over the rolled edge 12 of the body 30 and thus held in position by the resiliency of this edge 21. From this position, by forcing the cover upwardly, the edge will expand to permit detachment of the cover from position. And in order that this cover may not 35 rotate I have provided recesses 24 in the body and projections 25 in the cover to extend into these recesses and interfit therewith to prevent rotation of the cover.

This cover member may carry any character 40 or insignia 26 and thus I may use a cover with any desirable initial or emblem thereon for ornamenting the fastener. Also, by this construction I may snap the cover into position at the time a sale of the article carrying 45 the body may be sold so that the desired ornament or the initial desired may be had without the necessity of the merchant carrying in stock a full line of goods, each with a different character thereon.

50 In some instances, the socket for the stud of a snap fastener is not necessary as it is merely desirable to mount an initial in position on some article such as a bag or the like in which case it is unnecessary to have the socket in 55 the securing means, such as illustrated at 16, and any means for securing the body member to which the initial carrying plate is attached may be used.

By this arrangement the portion which is 60 secured to the article, such as a bag or the like, is mounted in position at the factory where the tools and presses for applying suitable pressure are available. The bags are then delivered to the retail merchant along with 65 the complete set of characters such as initials

or the like which may be snapped into position upon the article, each in accordance with the individual desire of the retail customer.

The foregoing description is directed solely towards the construction illustrated, but I 70 desire it to be understood that I reserve the privilege of resorting to all the mechanical changes to which the device is susceptible, the invention being defined and limited only by the terms of the appended claims. 75

I claim:

1. A fastener device having two parts, each engaging opposite surfaces of a material to which it is attached and with parts of one extending through the material and secured to parts of the other, a cover member for one of said parts, resilient fingers on said cover member having a beaded portion so shaped as to provide an inner surface of a different contour than the outer surface of the part to be covered thereby, whereby the beaded portion of said fingers engages the part to be covered along a definite line of contact. 80

2. A fastener device having two parts, each engaging opposite surfaces of a material to which it is attached and with parts of one extending through the material and secured to parts of the other, one of said parts having an undercut edge, a cover member for said undercut part, resilient fingers on said cover member having a beaded portion of such a size as to engage along the surface of said undercut edge and so shaped on its engaging surface as to engage said undercut edge on a 95 definite line of contact. 100

3. A fastener device having two parts, each engaging opposite surfaces of a material to which it is attached and with parts of one extending through the material and secured to parts of the other, one of said parts having an undercut edge, a cover member for said undercut part, resilient fingers on said cover member of such a size as to engage along the surface of said undercut edge, said fingers being rolled inwardly to present a convex engaging edge to engage said undercut edge on a definite single line of contact. 105

4. A snap fastener socket device having a body part and a socket part, a cover member, 110 said cover member being provided with resilient fingers rolled inwardly on their edge and arranged to engage said body part along a single line of contact and attachable and detachable therefrom by reason of the resiliency 115 of said fingers. 120

5. A fastener device having a body member and a securing element therefor, a detachable cover member over said body member, and recesses on one member and projections on the 125 other member interfitting with each other to prevent relative rotation of said members.

6. A member having a body part with a recess therein and a securing part, a cover over 130 said body part provided with a finger to en-

ter said recess to prevent relative rotation of said members.

7. A device comprising a body member, means for securing the body member in position, a member provided with a character thereon, means for detachably mounting said character member on said body member to cover the same, means to prevent relative rotation of said members, said means comprising interfitting portions between said members.

In testimony whereof I affix my signature.

ALFRED H. SMITH.
